THREAD CONTROL FOR WEFT
REPLENISHING LOOMSRichard G. Turner, Worcester, Mass., assignor to
Crompton & Knowles Loom Works, Worcester,
Mass., a corporation of Massachusetts

Application April 7, 1951, Serial No. 219,778

14 Claims. (Cl. 139—256)

1

This invention relates to improvements in weft replenishing looms and it is the general object of the invention to provide improved means to effect removal of the thread left by the incoming bobbin incident to a weft replenishing operation of the loom.

In a known type of bobbin changing loom picking of a freshly replenished shuttle ordinarily leaves a thread extending from a pneumatic thread holder into the warp shed. On the next beat-up of the lay after replenishment part of this thread is incorporated into the fabric and the remainder of it, extending from the cloth selvage to the thread holder, is placed over a stationary retainer or hook. At some later time in the loom operation the thread is cut at the selvage and should be removed pneumatically by the thread holder to prevent it from being dragged into the warp shed. When the thread is coarse or hairy difficulty is experienced in retrieving it by the pneumatic thread holder due partly to its length and also to the fact that it is likely to stick to adjacent threads.

It is an important object of the present invention to provide two pneumatic controls for the thread of the incoming bobbin, one control being relatively near the selvage and the other being the aforesaid thread holder located beyond the magazine with respect to the cloth, and provide means for cutting the thread between the pneumatic controls so that each of the controls can remove a part of it, thereby reducing the length of thread to be removed by the thread holder.

Heretofore I have proposed a thread control system wherein thread cutter mechanism is provided to cut the incoming thread in the event that it becomes entangled or matted with the outgoing thread at the time of cutting at the selvage, but that control depends for its cutting operation upon entanglement of the incoming and outgoing threads, and will not cut the incoming thread unless the latter has been moved to an abnormal position by the outgoing thread due to the fact that the two threads are entangled. It is another object of the present invention to provide a thread cutter to cut the incoming thread when the latter is in its normal position following the first beat-up after a replenishing operation. This feature of the invention will operate whether or not there is matting of the two threads when they are cut at the selvage.

It is a further object of the invention to locate the aforesaid stationary hook or thread retainer between the two pneumatic devices so that the part of the incoming thread extending from the

2

retainer to the selvage can fall toward the intake mouth of the pneumatic remover device near the cloth when the thread is cut at the selvage.

It is a still further object of the invention to provide a thread cutter which in the preferred form of the invention will include a cutting blade on the bobbin transerrer arm for cooperation with a surface or anvil below the thread to cut the latter incident to a replenishing operation.

10 The cutter is preferably mounted for yielding motion with respect to the transerrer arm and is brought into action as the latter nears the bottom of its bobbin transferring stroke. The anvil can conveniently be located on the lay to move forwardly to a position under the thread for cooperation with the thread cutter as the lay beats up on a bobbin changing operation of the loom. In this feature of the invention the anvil is preferably through not necessarily located between the stationary retainer hook and the pneumatic thread holder, and an incoming thread placed over the hook incident to one replenishing operation will be cut on the next replenishing operation.

25 The pneumatic device adjacent to the cloth may conveniently take the form of a thread remover for the outgoing thread, in which event it will be associated with movable hook means such as shown in my prior Patent No. 2,194,531 to draw the thread of the outgoing bobbin forward-

30 ly where it can be drawn into the mouth of the pneumatic thread remover. When the incoming thread is cut at the selvage it is likely to wrap around the movable hook so that it cannot be drawn into the remover. In order to prevent this wrapping of the thread it is a further object of the invention to provide a guard or the like which will prevent entanglement of the incoming thread with the movable hook.

In the modified form of the invention the 40 thread cutter is of the scissor type operated by the transerrer arm and does not require the aforesaid anvil. The cutter of the modified form, however, will cut the incoming thread at a point along the course which it normally occupies.

45 In the accompanying drawings, wherein two forms of the invention are set forth,

ing the cutter of the preferred form on the trans-
ferrer arm engaging the cutting anvil on the lay
incident to a weft replenishing operation, 15

Fig. 14 is a view similar to part of Fig. 1 showing
a modified form of thread cutter,

Fig. 15 is a diagrammatic view similar to Fig. 12
showing the position of the modified cutter mech-
anism with respect to the thread holder and the
stationary thread hook, and 20

Fig. 16 is a diagrammatic front elevation show-
ing a lay adapted for two shuttles with either or
both of which the invention can be used. 25

Referring particularly to Figs. 1 and 2, the loom
frame 1 supports a stand 2 on which a magazine
M is pivoted as at 3. The magazine has front and
back stacks of reserve bobbins 4 and 5, respec-
tively, which move downwardly by gravity to their
respective transfer positions and have attached to
them weft threads W leading to a pneumatic
thread holder device H. The loom has a lay 6 pro-
vided with a shuttle box 7 to receive either of two
shuttles S or S1, one at a time, see Fig. 16. Pick-
ing mechanism shown generally at 8 is provided
for picking the shuttle out of the shuttle box 7. 30

The front wall of the shuttle is provided with a
metallic plate 10 across which extends the thread
T of bobbin B in the shuttle. On a bobbin chang-
ing beat of the lay this plate cooperates with a
cutter blade 11 controlled by the transerrer arm
to cut the outgoing thread OT shown in Fig. 10
and being the last part of the thread T attached
to bobbin B when the latter is replaced in well-
known manner by a bobbin from the magazine.
A bobbin transerrer arm 12 is pivoted on station-
ary pivot stud 13 fixed with respect to the stand 2.
A latch 14 forming part of the transerrer arm is
normally below the path of a bunter 15 on the lay,
but on a weft replenishing beat of the loom the
latch is raised in known manner to be engaged by
the bunter to effect downward motion of the
transerrer arm, or motion in a counter-clock-
wise direction as viewed in Fig. 1, as the lay beats
up while moving to the right as viewed in Fig. 1.
The transerrer arm will move the lowest reserve
bobbin under it into the shuttle in box 7 and
expel the depleted bobbin on a replenishing beat
of the loom.

When a fresh bobbin is inserted into a shuttle
its incoming thread or weft end IT will extend
from it to the pneumatic thread holder device H,
which serves also as a thread remover, and when
the replenished shuttle is picked this incoming
thread IT will be carried into the warp shed on
the first picking operation after replenishment.
On the next beat-up of the lay that part of the
incoming thread in the shed will be incorporated
into the fabric and the remainder of it will ex-
tend from the selvage of the fabric F to the
thread holder H.

The lay is provided with a front wall 20 to
which is secured a forwardly extending thread 75

placer 21, see Fig. 7, having a thread advancing
edge 22 under a hook 23 which limits upward mo-
tion of the thread IT with respect to the thread
placer. The loom also has a stationary thread
retainer, such as a hook 24, having an upwardly
and forwardly inclined surface 25 leading to a
thread notch 26 which will be somewhat above
the hook 23 when the lay is on front center.

On the first beat-up of the lay after a bobbin
changing operation the incoming thread IT will
be engaged by the surface 22 and will be moved
forwardly and up along the surface 25 of the sta-
tionary retainer 24. Since the pneumatic holder
H will hold thread IT taut under these conditions
the thread IT will remain in engagement with
the thread placer and will rise along the surface
25 and fall into notch 26 as the lay reaches front
center position. On the next backward motion of
the lay the placer 21 will move away from the
thread IT and the latter will then extend along
its normal path or course from the cloth selvage
27 over retainer 24 to the thread holder H. On
the following beat-ups of the lay the hook 23 will
traverse a path below the thread IT.

The loom is provided near the selvage 27 with
selvage thread cutter mechanism designated at
30 normally set forward of the reed 31 of the lay.
This cutter mechanism 30 will eventually cut
both of the threads OT and IT, ordinarily on a
forward beat of the lay, after the cloth by its for-
ward motion has moved these threads into the
range of operation of the selvage cutter. Both of
these threads should be removed from the loom
to prevent them from being drawn into the warp
shed. 35

A pneumatic thread remover device R some-
what similar to the remover shown in my prior
Patent No. 2,194,531 is mounted in stationary po-
sition and performs the function described in
40 that patent of attracting first that part of the
outgoing thread OT extending from the cutter
blade 11 to the remover R, and then subsequently
removing the remainder of this thread which ex-
tends from the remover to the thread cutter 30
when the latter cuts the thread at the selvage. 45

There is provided a movable thread hook
means 32 which is normally in forward position
but is moved rearwardly under the outgoing
thread OT on a replenishing beat of the loom and
then moves the thread forwardly toward the re-
mover R. In the present instance the hook de-
rives this back and forth motion from the shuttle
50 position detector or revoker arm 33 which is
part of the replenishing mechanism and may op-
erate for instance as shown in prior Patent No.
2,219,767. 55

Except as noted hereinafter the mechanism
thus far described is of usual construction and
operates in the ordinary manner.

In carrying the preferred form of the invention
into effect the front shuttle box wall 20 has se-
cured thereto at 34 an anvil 35 having an up-
wardly facing surface 36 across which the in-
coming thread IT when following its normal
course will extend from the retainer hook 24 to
60 the thread holder H when the lay is on front
center position. The anvil, which may be made
of steel, is part of an additional or second thread
cutter mechanism designated generally at 37
spaced farther from the selvage than the selvage
cutter mechanism 30 and located preferably be-
tween the retainer and holder H. The cutter
mechanism 37 includes a guide bracket 38 secured
65 as at 39 to the transerrer arm 12, see Fig. 13.
Mounted for vertical sliding movement in the

bracket 38 is a rod 40 having secured thereto a collar 41 located between upper and lower slide bearings 42 and 43 of the support 38. A compression spring 44 between bearing 42 and collar 41 normally urges the rod 40 downwardly as shown for instance in Fig. 8. A cutter blade 45 is mounted for limited angular motion on the bottom of rod 40 by means of a pin 46. The cutter blade is normally in its raised inoperative position but will descend with the transerrer arm on a bobbin changing beat of the loom to cause the cutter blade 45 to engage the surface 36 of the anvil a short time before the lay reaches front center and cut thread IT extending across the anvil.

The thread remover device R, see Fig. 3, is hollow to provide an air and thread passage 50 the lower rear end of which opens to the atmosphere through a thread intake mouth 51 below the thread IT. Passage 50 is in a tubular member 52 secured to a depending arm 53 slotted as at 54 and held by a screw 55 to an arm 56, see Fig. 4. The latter arm is part of a carrier designated generally at 57 and shown in Fig. 5. This carrier has a hub 58 mounted on the previously mentioned stud 13 and secured thereto in angularly readjusted position by a screw 59. The upper part of tubular member 52 is fitted to a hose 60 leading to a source of subatmospheric pressures (not shown) preferably the same source to which thread holder H is connected. This source may be a pump such as is shown in previously mentioned Patent No. 2,194,531.

A guard 65 for hook 32 is held in adjusted position in bearing 66 on carrier 57 by a set screw 67. The guard may be formed as a rod having a hole 68 in the lower end thereof to receive the point 69 of hook 32. Under normal conditions the guard 65 will be in the position shown in Fig. 5 with its lower end close to but preferably spaced slightly from the point of hook 32 when the latter is in its normal forward position. When hook 32 moves rearwardly it leaves the guard and if it should have any excess movement when returning to its forward position the point 69 will enter hole 68.

When the lay is on front center on a bobbin changing operation the parts will be in the position shown in Fig. 10 with the hook 32 and revoker 33 in rear position, and the cutter blade 11 against plate 10 of the shuttle to cut the outgoing thread OT. After the freshly replenished shuttle is picked to the opposite side of the loom the parts will be as shown in Fig. 11 with the hook 32 returned to its normal forward position to move thread OT to the intake mouth 51 and thread IT extending from holder H into the warp shed W. When the lay reaches front center on the following beat-up both threads OT and IT will be attached to the cloth selvage 27 as shown in Fig. 12, thread OT extending into the remover R and thread IT extending across anvil 35 to the thread holder H.

The first beat-up of the lay after a bobbin replenishing operation will leave the thread IT extending from the stationary hook 24 to the selvage over the tubular member 52 above and forward of the intake mouth. A downwardly and rearwardly directed thread guide leads to the intake mouth, this guide as shown herein being the inclined upper surface 75 of the tubular member 52, as shown for instance in Fig. 12. The cutting of both of the threads OT and IT by the cutter mechanism 30 will occur several picks after a replenishing operation and generally while the

hook 32 is in its forward position. When the selvage cutter mechanism 30 severs the thread IT that part of the latter extending from the retainer hook 24 toward the selvage of the cloth 5 will fall along guide surface 75 to the intake mouth 52 and will be pneumatically drawn into the latter. Should the thread be resilient and when cut tend to spring or snap toward hook 32 the guard 65 will prevent the thread from wrapping around the hook.

The incoming thread IT will then be held pneumatically at two points as a result of the normal operation of the mechanism, one point being at the pneumatic thread holder device H 15 and the other at the pneumatic remover device R. The pneumatic tension on the two ends of this thread IT will hold it taut across the anvil 35 as the lay beats up. This condition will prevail until the next bobbin transfer operation, 20 whereupon descent of the transerrer arm 12 will cause the cutter blade 45 to strike and sever the thread IT extending across surface 36. The thread IT will then be in two parts one of which 25 will be drawn into the pneumatic thread holder H and the other part, or remainder, will be sucked into the remover R. These two parts of thread IT, each shorter than the original thread IT, can be readily removed by their respective pneumatic devices.

In order to prevent the thread IT from moving forwardly along surface 36 out of the range of the cutting operation of blade 45 a thread stop 76 is secured to the carrier 57 and is located preferably on the side of the anvil 35 between the latter and the thread holder H and forward of the thread IT. That part of the thread IT adjacent to the anvil when the lay is on front center is therefore positioned by the hook 24 and the stop 76 and will extend across the surface 36 within the cutting range of blade 45.

My prior Patent No. 2,448,161 makes provision for cutting the incoming thread but only if part of it assumes an abnormal position as might result from its becoming matted with the outgoing thread OT when cut by the selvage cutter and then drawn into a pneumatic thread remover. In the present instance the cutter blade 45 and surface 36, and also the thread remover R, are intentionally located along the normal path or course of thread IT extending from the selvage over hook 24 to the thread holder H. Because of this relation the incoming thread, whether or not it is matted with the outgoing thread by the cutter mechanism 30, will be held pneumatically at two points and will be severed by a cutter mechanism located along its normal path.

The modified form of the invention utilizes a scissor type of thread cutter mechanism, designated generally at 80, to replace the anvil 35 and blade 45. This cutter mechanism, shown in Figs. 14 and 15, may be similar, except for its position relative to thread IT, to the cutter shown in my prior Patent No. 2,448,161.

Referring to Figs. 14 and 15, the transerrer arm has secured thereto a small bearing stand 81 in which is held a stem 82 to which is secured a cutter blade 83. A second blade 84 pivoted on the stem at 85 is normally held in open position relative to blade 83 by a spring 86. A flexible actuator, such as a leather thong 87, is connected at one end to the movable blade and has its other end held in fixed position, as at 88.

The cutter mechanism 80 is preferably located between hook 24 and thread holder H and will be in high inoperative position when the trans-

transferrer arm is in its raised position. When the transferrer arm descends the blades 83 and 84 will straddle thread IT and then thong 87 will move the movable blade to its closed or cutting position to sever thread IT as the transferrer arm reaches its low position. The modified cutter mechanism 89 will operate in substantially the same position as does the preferred form to cut the thread IT between the points at which it is pneumatically held. In the modified form, which does not employ the anvil, the thread positioner 76 can be omitted.

When the invention is applied to a loom operating with two or more shuttles which are active alternately it is possible for two weft replenishing operations, and therefore two operations of the thread cutter mechanism 37 or 80 occur before the selvage cutter 30 has opportunity to cut the first incoming thread corresponding to the first replenishing operation. Thus, if the shuttle S is replenished on a given pick it will leave a thread extending from the thread holder to the selvage and if shuttle S₁ is replenished a short time later the thread left by the first replenishing operation will be cut between the pneumatic devices before the selvage cutter, which ordinarily cuts several picks after a replenishment, has had opportunity to cut the thread from the selvage. Under these conditions that part of the first thread extending from the cutter mechanism 37 or 80 to the selvage will fall along guide 75 toward the intake mouth and be drawn into the latter while the thread is still attached to the selvage. Cutting by the selvage cutter a few picks later will then enable the part of the thread between the selvage and the remover device to be drawn into the latter.

While the previously described closely occurring successive transfers are not uncommon in a loom such as set forth herein the more likely order of operation is that a second replenishment will occur after the selvage cutter has cut the thread left by the first replenishment, in which event the first thread when cut adjacent to the selvage, will fall along guide 75 toward the intake mouth of the remover before the thread is cut by mechanism 37 or 80. It will thus be seen that depending upon the time elapsing between two weft replenishing operations one or the other of the thread cutting mechanisms will be the first to operate on the thread left by the first shuttle replenished.

From the foregoing it will be seen that the invention sets forth simple means for holding the incoming thread pneumatically at two points along its normal path and cutting the thread between these points by thread cutter mechanisms 37 or 80. It will further be seen that the pneumatic remover R is so located that it will always attract a part of the incoming thread as soon as the latter is released from the selvage whether or not this thread has become entangled with the outgoing thread. That part of the incoming thread extending from the retainer hook 24 to the selvage will normally extend over the remover R and also over the guard 65, and when this thread is cut at the selvage it will fall along guide surface 75 toward the intake mouth 51 without likelihood of becoming entangled with the hook 32. The inclined guide surface 75 is shown herein on the tube 52, but this is not a necessary relation, since the guide could be separate from the remover R. During the cutting of the incoming thread the anvil will have a slight back and forth motion with respect to the blade 45 which will assist in severing of the thread. It is to be under-

stood that the spring 44 will always yield somewhat during a cutting operation of the blade 45 so that the latter will remain in engagement with the cutting surface 36 during an appreciable amount of back and forth motion of the lay while the transferrer arm is in or near its lowest position. The cutter mechanism 80, as well as the preferred form of cutter, will have a range of cutting action located along the path of thread IT when the latter is in the position it normally occupies after the first lay beat up following a bobbin changing operation. Also, whether the cutter 30 or 37 cuts the incoming thread first the guide 75 will enable the end of the thread over the remover to fall to the intake mouth.

Having thus described the invention it will be seen that changes and modifications of the foregoing specific disclosure may be made without departing from the spirit and scope of the invention.

What is claimed as new is:

1. In a weft replenishing loom having a thread extending from a pneumatic thread holder and remover to a retainer and thence to the selvage of the cloth after the first beat-up of the lay following a bobbin changing operation, a pneumatic thread removing device having an intake mouth below that part of the thread extending from the retainer to the selvage, a selvage thread cutter mechanism cutting the thread at the selvage, guide means under the thread along which that part of the thread between the selvage and the pneumatic device falls toward and is drawn into said intake mouth, and a second thread cutting mechanism operative to cut the thread between the pneumatic thread holder and the pneumatic device, the thread holder thereupon removing that part of the thread between the second thread cutter mechanism and the thread holder and the pneumatic device removing that part of the thread extending from the second thread cutting mechanism to said mouth.

2. The structure set forth in claim 1 wherein said second thread cutting mechanism is located between said retainer and the pneumatic thread holder.

3. The structure set forth in claim 1 wherein said retainer is a stationary hook and said second thread cutting mechanism is located between said hook and the pneumatic thread holder.

4. In a weft replenishing loom having a thread extending from a pneumatic thread holder over a stationary retainer to the selvage of the cloth after the first beat-up of the lay following a bobbin changing operation, a pneumatic thread remover device having a thread intake mouth, a thread guide extending downwardly and toward said mouth under that part of the thread extending from the retainer to the selvage, and thread cutting mechanism cutting the thread at a point between the pneumatic thread holder and said pneumatic thread remover device, the thread holder thereupon attracting the part of the thread extending from the cutting mechanism to the thread holder and the part of the thread between the cutting mechanism and the selvage falling along said guide to said intake mouth and being drawn pneumatically into the latter.

5. In a weft replenishing loom having a thread extending from a pneumatic thread holder over a stationary retainer to the selvage of the cloth after the first beat-up of the lay following a bobbin changing operation, a pneumatic thread remover device in which subatmospheric pressures are created and having a downwardly and

rearwardly inclined thread guide surface leading to a thread intake mouth in the remover device, said surface being under that part of the thread leading from the retaining means to the selvage, and thread cutting mechanism to part the thread between the thread holder and said pneumatic device, the thread holder thereupon attracting that part of the thread between the thread holder and the thread cutting mechanism and the part of the thread extending from the thread cutting mechanism to the selvage falling downwardly and rearwardly along said surface on the thread remover device to said intake mouth to be drawn into the latter.

6. In a weft replenishing loom wherein a thread remains after a freshly replenished shuttle is picked following a replenishing operation of the loom, two pneumatic devices for said thread into one of which the thread extends and the other of which is intermediate the first device and the cloth selvage and has an intake mouth adjacent to the thread, and thread cutting mechanism intermediate said pneumatic devices cutting the thread, whereupon part of the thread is removed by the first device and a part of the remainder of the thread extending from the cutting mechanism to the intake mouth is drawn into the latter.

7. The structure set forth in claim 6 wherein additional thread cutting mechanism is provided at the selvage to cut said remainder of the thread from the cloth being woven, said other device thereupon drawing that part of said remainder extending from the selvage to the intake mouth into the latter.

8. In a weft replenishing loom wherein the outgoing bobbin incident to a replenishing operation leaves a thread extending from the selvage and the incoming bobbin leaves a thread extending from a pneumatic thread holder to the selvage on the first beat-up of the lay after weft replenishment, a pneumatic thread remover between the thread holder and the selvage having an intake mouth adjacent to said incoming thread, means moving the outgoing thread to a position adjacent to said intake mouth, whereupon part of the thread of the outgoing bobbin is drawn pneumatically into said mouth, and thread cutter mechanism intermediate the thread holder and thread remover effective to cut the incoming thread, whereupon that part of the thread extending from the thread cutter mechanism to the thread holder is drawn into the latter and that part of the remainder of the incoming thread extending from the thread cutter mechanism to the intake mouth is drawn into the latter.

9. The structure set forth in claim 8 wherein additional cutting means is located adjacent to the selvage and cuts both threads from the selvage, whereupon the remaining part of the outgoing thread and that part of the incoming thread extending from the selvage to the intake mouth are drawn into the latter.

10. The structure set forth in claim 8 wherein said means acting on the thread of the outgoing bobbin is a hook, and a guard is provided for said hook preventing either of said threads from wrapping around the hook.

11. In a weft replenishing loom in which a 70 thread is left by a freshly replenished shuttle when it is picked, two thread cutting mechanisms,

one adjacent to the selvage of the cloth being woven and the other being spaced from the selvage, and two pneumatic thread removing devices, one located intermediate said mechanisms and having an intake mouth for the thread and the other being beyond the other mechanism with reference to the selvage, the thread extending from said other device over said one device to the selvage, the thread when cut by said one mechanism falling toward and being drawn into said mouth and when cut by the other mechanism being separated into two parts one of which is drawn into the first device and the other part of which is drawn into the other device.

15 12. The structure set forth in claim 11 wherein the loom has a lay and a bobbin transerrer arm and said other of the thread cutting mechanisms includes an anvil on the lay moving to a position under the thread as the lay beats up and a cutter blade moved against the anvil by the transerrer arm when the latter has a bobbin transferring operation.

20 13. The structure set forth in claim 11 wherein the loom has a bobbin transerrer arm and said other of the thread cutting mechanisms includes scissor cutter blades moved to position to cut the thread and then operated to cut the thread by the transerrer arm when the latter has a bobbin transferring operation.

25 14. In a weft replenishing loom operating with two shuttles and wherein the loom replenishes the weft of one of the shuttles on a given pick of the loom and replenishes the weft of the second shuttle on a subsequent pick, a pneumatic thread holder, a thread removing pneumatic device between the thread holder and the selvage of the cloth being woven, the loom having a thread lying along a path extending from the thread holder over the pneumatic device to the selvage subsequent to the beat-up following replenishment of the first shuttle, and two thread cutter mechanisms arranged along said path located on opposite sides of the pneumatic device, one of said cutter mechanisms being adjacent to the selvage and cutting said

30 35 thread at the selvage several picks after replenishment of the first shuttle, the other cutter mechanism being located between the remover device and the thread holder and cutting said thread incident to replenishment of the second shuttle, the part of said thread extending between the selvage and pneumatic device falling toward and being drawn into the latter if said one cutter mechanism cuts said thread prior to replenishment of the second shuttle, and the part 40 45 of said thread between the pneumatic device and said other cutter mechanism falling toward and being drawn into said pneumatic device if the second shuttle is replenished prior to cutting of said thread by said one cutter mechanism.
